(57) **CLAIM**

The ornamental design for a toy construction connector kit, as shown and described.

DESCRIPTION

FIG. 1 is a perspective view of a toy construction connector kit showing my new design.

FIG. 2 is a front elevational view thereof, which is a mirror image of a rear elevational view thereof.

FIG. 3 is a side elevational view thereof.

FIG. 4 is a side elevational view of a side opposite that shown in FIG. 3.

FIG. 5 is a top plan view thereof; and,

FIG. 6 is a bottom plan view thereof.

The broken lines in the drawings are for the purpose of illustrating environment only and form no part of the claimed design.

1 Claim, 6 Drawing Sheets(56)
